Primary Examiner — Freda S Nunn(74) *Attorney, Agent, or Firm* — Ladas & Parry LLP(57) **CLAIM**

We claim the ornamental design for the digital information display device, as shown and described.

DESCRIPTION

FIG. 1 is the front perspective view of the digital information display device showing our new design in one configuration;

FIG. 2 is the front view thereof;

FIG. 3 is the rear view thereof;

FIG. 4 is the left-side view thereof;

FIG. 5 is the right-side view thereof;

FIG. 6 is the top plan view thereof;

FIG. 7 is the bottom plan view thereof;

FIG. 8 is a perspective view thereof showing a second configuration of the device in a folded position;

FIG. 9 is a perspective view thereof showing a third configuration of the device in an expanded position;

FIG. 10 is an enlarged view of the left hand end of FIG. 7; and,

FIG. 11 is an enlarged view of the right hand end of FIG. 7. The short dash-dash broken line in the figures shows unclaimed portions of the digital information display device, the dot-dot-dash broken line in FIGS. 7, 10 and 11 encircling a portion of the claimed design is for illustrating the enlargement, and the dot-dash broken line in the figures represents a boundary of the claimed design; the broken lines form no part of the claimed design.
